UNITED STATES PATENT OFFICE.

JOHN P. COLEMAN, OF OGLESBY, ILLINOIS.

FAN ATTACHMENT FOR SEWING-MACHINES AND THE LIKE.

No. 851,651.

Specification of Letters Patent.

Patented April 30, 1907.

Application filed November 20, 1906. Serial No. 344,281.

To all whom it may concern:

Be it known that I, JOHN P. COLEMAN, a citizen of the United States, residing at Oglesby, in the county of LaSalle, State of Illinois, have invented certain new and useful Improvements in Fan Attachments for Sewing-Machine and the Like; and I do hereby declare the following to be a full, clear, and exact description of the invention, such as will enable others skilled in the art to which it appertains to make and use the same.

This invention has reference to fan attachments for use in connection with sewing and other machines; and the invention has for its chief object to provide a simple, and effective device of the class described, which can be quickly and easily applied to any kind of machine and can be driven from the main drive-shaft of the machine.

To this end, the invention consists in the provision upon the machine table of a pedestal having a pair of telescoping sections mounted thereon, the inner of which is provided at its upper end with a hollow tubular bearing-member, in which is rotatably mounted a bearing-sleeve provided with a driving-pulley having a belt connection with the main-shaft of the machine; there being a fan-spindle mounted within the bearing-sleeve and provided with a fan and fan-casing.

A further improvement consists in the provision of a clutch member upon the opposite end of the fan-spindle, adapted to be moved into and out of engagement with a clutch member formed on the bearing-sleeve for effecting the rotation of the fan-spindle.

The invention will be readily understood from the following detailed description, and its preferred embodiment is illustrated in the accompanying drawings, in which like parts are designated by corresponding reference numerals in the several views, and in which—

Figure 1 is a side elevation of the fan attachment in place. Fig. 2 is a top plan view thereof. Figs. 3, 4, and 5 are horizontal sections taken respectively on the lines 3—3, 4—4, and 5—5 of Fig. 1.

Referring to the drawings, and more particularly to Fig. 1, there is shown a portion of a sewing machine including a machine body 14 mounted upon a table 15 of the usual type, and provided with a main shaft 16 carrying the usual fly-wheel and a grooved pulley 17 connected by a belt 18 with a

similar pulley mounted on the treadle-operated crank shaft of the machine (not shown). As the above parts are common to all sewing machines, further description thereof is unnecessary.

Mounted upon the table extension 19 is a pedestal 20, to which is secured a tubular casing 21, vertically disposed thereon and having a tubular member 22 slidable therewithin and provided with a longitudinal groove 23. The casing and tubular member may thus be adjusted with respect to each other, being retained in such position by means of a set-screw 24, passing through the enlarged upper end of the casing and having its inner end fitting in the groove 23. The upper end of member 22 is provided with a bore 25. 26 designates a horizontally-disposed hollow bearing-member having a depending stem formed with a reduced portion 27 fitting in said bore, whereby the position of member 26 may be adjusted with respect to member 22, said parts being retained in position when adjusted by means of a set-screw 28, working through an opening in the upper portion of member 22 and impinging against the reduced portion 27 of member 26.

Rotatably mounted within member 26 is a hollow bearing-sleeve 29, provided with collars 30 mounted thereon and located on opposite sides of member 26 for preventing endwise movement of said sleeve. A grooved belt-pulley 31 is secured to one end of said sleeve while its opposite end is toothed, as at 32, to form one member of a clutch. Loosely mounted within said sleeve is a fan-spindle 33 carrying a fan 34 on one end and having its opposite end threaded, as at 35. An internally threaded hand-wheel 36 is mounted for longitudinal movement on the threaded end of the spindle and is formed on its inner face with an extension 37, the outer end of which is serrated and serves as the opposite member of the clutch.

39 designates a short horizontal stub-shaft journaled in bearings provided in the pedestal 20 and in a short upright 38 secured to the table 15, said stub-shaft being provided with a compound-pulley, the larger member 40 of which is connected by a belt 41 with the pulley 31 on the bearing-sleeve 29, while its smaller member 42 is connected by the belt 18 with the pulley on the treadle-operated crank-shaft.

In the operation of the machine, rotation of the crank-shaft pulley, effected through

- the treadle, drives belt 18, which in turn rotates pulleys 42 and 17, the latter of which being carried by the shaft 16, operates the machine proper. The rotation of the 5 pound-pulley by means of its belt-connection with the pulley 31 on sleeve 29 effects the rotation of the latter, which movement is communicated to the fan-spindle when the clutch member 37 of the hand-wheel 36 is moved 10 into engagement with the clutch member 32 of the sleeve.

While the invention has been shown and described in connection with a sewing machine, it will be readily understood that it 15 may be attached with equal facility to dental machines and other machines of a like nature.

The fan-spindle may be provided with a casing 43, surrounding the fan, and various 20 other changes may be made in the size, proportion, and arrangement of the several elements of the machine without departing from the scope of the invention.

What is claimed, is—

- 25 1. In a fan attachment for sewing machines and the like, the combination, with a pedestal on the table of the machine, of a standard mounted on said pedestal and provided with a horizontally disposed hollow 30 bearing at its upper end; a sleeve rotatably mounted within said bearing and provided with means for preventing its endwise movement with respect thereto; a clutch member formed on one end of said sleeve; a fan- 35 spindle rotatably mounted within said sleeve; a fan secured to one end of said spindle; a longitudinally movable clutch member carried upon the threaded end of said spindle and adapted to be moved into and out of engagement with said first-mentioned clutch member; and a belt connection between said pulley and the drive wheel of the machine for rotating said sleeve. 70

adapted to be moved into and out of engagement with said sleeve clutch member; and 40 means for driving said sleeve from the machine wheel.

2. In a fan attachment for sewing machines and the like, the combination, with a pedestal on the table of the machine, of a 45 tubular casing mounted upon said pedestal; a tubular member slidably mounted within said casing and provided with a bore at its upper end; means for securing said tubular member in adjusted position within said casing; a horizontally disposed hollow bearing member having a depending portion fitting rotatably in said bore; means for securing said bearing member in adjusted position with respect to said tubular member; a 50 sleeve rotatably mounted within said bearing and provided with means for preventing its endwise movement therein; a clutch member formed on one end of said sleeve; a pulley secured to the opposite end of said sleeve; a fan-spindle rotatably mounted within said sleeve, and having its end adjacent said clutch member screw-threaded; a fan carried by said spindle at one end; a longitudinally movable clutch member carried upon the threaded end of said spindle and adapted to be moved into and out of engagement with said first-mentioned clutch member; and a belt connection between said pulley and the drive wheel of the machine for rotating said sleeve. 70

In testimony whereof, I affix my signature, in presence of two witnesses.

JOHN P. COLEMAN.
